US0D1041421S

(12) **United States Design Patent** (10) **Patent No.:** **US D1,041,421 S**
(45) **Date of Patent:** **** Sep. 10, 2024**

(54) **ELECTRICAL CONTACT ELEMENT**

(71) **Applicant:** **STÄUBLI ELECTRICAL CONNECTORS AG**, Allschwil (CH)

(72) **Inventors:** **François Saugues**, Villette d'Anthon (FR); **Dominic Bürgi**, Windsor (CA)

(73) **Assignee:** **STÄUBLI ELECTRICAL CONNECTORS AG**, Allschwil (CH)

(**) **Term:** **15 Years**

(21) **Appl. No.:** **35/514,355**

(22) **Filed:** **Nov. 25, 2021**

(80) **Hague Agreement Data**

Int. Filing Date: **Nov. 25, 2021**

Int. Reg. No.: **DM/217619**

Int. Reg. Date: **Nov. 25, 2021**

Int. Reg. Pub. Date: **May 27, 2022**

(30) **Foreign Application Priority Data**

Jun. 1, 2021 (CH) 146.138

(51) **LOC (14) Cl.** **13-03**

(52) **U.S. Cl.**

USPC **D13/133; D13/154**

(58) **Field of Classification Search**

USPC D13/118, 123, 133, 154, 199

(57) **CLAIM**

The ornamental design for electrical contact element, as shown and described.

DESCRIPTION

1. Electrical contact element

5. Electrical contact element

9. Electrical contact element

13. Electrical contact element

17. Electrical contact element

21. Electrical contact element
